UNITED STATES PATENT OFFICE.

CONRAD JOBST, OF TOLEDO, OHIO, ASSIGNOR TO THE AMES BONNER COMPANY, OF TOLEDO, OHIO, A CORPORATION OF MICHIGAN.

BRUSH-MAKING MACHINE.

1,144,712.

Specification of Letters Patent. Patented June 29, 1915.

Application filed November 24, 1913. Serial No. 802,683.

To all whom it may concern:

Be it known that I, CONRAD JOBST, a citizen of Germany, and a resident of Toledo, in the county of Lucas and State of Ohio, 5 United States of America, have invented a certain new and useful Brush-Making Machine; and I do hereby declare the following to be a full, clear, and exact description of the invention, such as will enable others 10 skilled in the art to which it appertains to make and use the same, reference being had to the accompanying drawings, and to the characters of reference marked thereon, which form a part of this specification.

15 This invention relates to brush-making machines and particularly to machines for the making of brushes of the compound or multiple bristle-tuft type, but is not restricted to such use, as it may be used in all 20 connections for which it may be adapted or appropriate.

The object of my invention is the provision of an improved machine of this character, whereby a plurality of brush-backs 25 of respective sets can be successively drilled or filled in a continuous operation, thus enhancing the practicability and commercial value of machines of this nature.

A further object of my invention is the 30 provision of a machine of this character adapted for the drilling and filling or either, of brush-backs of different forms and styles during a continuous or cycle of operation of the machine, thus enabling a single machine 35 to perform at one time the work of two machines.

A further object of the invention is the provision of simple and efficient mechanism for carrying and directing the movements of brush-backs or other work-pieces 40 when being acted on. Other objects and advantages of the invention will be apparent to those skilled in the art from a reading of the following detailed description thereof.

45 The invention is fully described in the following specification, and while in its broader aspect, it is capable of embodiment in numerous forms, one embodiment thereof is illustrated in the accompanying drawings, 50 in which.—

Figure 1 is a left side elevation of a machine embodying the invention. Fig. 2 is a front elevation thereof with parts broken away. Fig. 3 is a right side elevation of the 55 machine. Fig. 4 is an enlarged top plan

view thereof with parts broken away. Fig. 5 is an enlarged front elevation of the brush-back carrying slides and guide parts in assembled relation with a set of brush-back clamping-blocks broken away. Figs. 6 and 60 65 7 are top plan and end views thereof, respectively, and Fig. 8 is a diagram of one path of movement of the drilling or filler parts relative to an associated pair of brush-backs, the backs being shown as of different styles. 65

Referring to the drawings, 1 designates the portion of the machine frame which carries the parts and mechanisms embodying the features of my invention, and which is shown as being substantially U-shape, and 70 2 the frame part which is disposed in front of the part 1 at one side thereof and has the table part 2^a extending laterally from the left side of its top, said part 2—2^a carrying the drilling and filler mechanisms of the 75 machine, both of which mechanisms are commonly used in machines of this class, and which, in themselves, contain no patentable features. Of these mechanisms 3 designates a head or chuck for carrying a 80 drill 3^a, and 4 the filler nozzle, which drill-head and nozzle, in the present instance, are horizontally spaced as shown in Fig. 4.

Mounted for forward and backward movements in a suitable guide-way on the top of 85 the frame part 1 over the crotch or open portion thereof is a table 5, which is provided for a distance rearwardly from its forward end with an opening 5^a. A vertical guide-plate or part 6 is rigidly carried 90 by the table 5 at its forward end, and may be integral therewith or secured to the table in a separable manner, as by having lugs or arms 7 projecting rearwardly therefrom and bolted to the adjacent end of the table 95 5 at the sides of the opening 5^a therein. The guide-plate 6 extends above and below the plane of movement of the table 5.

A carrier-slide or head 8 is guided for vertical reciprocating movements by the 100 guide-plate 6 having its rear side portion in dove-tailed or other suitable sliding engagement therewith, as best shown at 8^a in Fig. 6. The carrier-head 8 is elongated transversely of the guide 6 with its ends projecting in opposite directions therefrom and is fashioned at its front side, preferably at the upper and lower edges thereof, to form a guide for the horizontal reciprocating movements of a slide-plate 9 which, in the 105 110

present instance, has dove-tailed engagement with the carrier-head 8, as best shown at 9^a in Fig. 7. The slide-plate 9 in turn carries a brush-back holder or carrying-plate 10 for horizontal sliding or reciprocatory movements relative thereto, being in dove-tailed or other suitable sliding connection with the front side thereof, as best shown at 10^a in Fig. 7.

19 The plates 9 and 10 are cut away or open at their central lower portions, as shown at 11 in Figs. 2 and 5 to enable them to straddle subjacent parts of the machine and to have free horizontal movements relative thereto, 25 and the guide-plate 6 also has its lower end bifurcated or vertically slotted, as at 12, for the same purpose.

The brush-back holder 10 is of suitable length, in the present instance, to accommodate 20 a set of two pair of brush-back clamping-blocks 13 at each side of the opening 11 therein, and the plate 9, which really forms a relatively movable backing-plate for the holder-plate 10, is preferably of approximately 25 the same length as such holder-plate, as shown in Figs. 5 and 6. The clamping-blocks 13 of the different pairs are mounted for relative vertical reciprocatory movements on respective dove-tail form of 30 guide-ribs 14 on the front side of the holder-plate 10, and each block has an apertured lug 15 projecting rearwardly therefrom into a registering vertical groove 16 in the associated guide-rib 14. A hand-screw 17 projects 35 down through each groove 16 and the lugs 15 therein and has right-hand threaded engagement with one lug and left-hand threaded engagement with the other lug to cause the blocks 13 of a pair to have relative to and fro movements upon a turning of the screw in one direction or the other. Each screw is anchored against longitudinal movements relative to the holder-plate 10, as indicated at 18, (Fig. 5) or in any other suitable 40 manner. Brush-back engaging clamping fingers 19 are carried by the blocks 13 in proper position to facilitate the clamping and holding of a brush-back by a pair of clamping-blocks 13, the arrangement of the fingers 19 being changed to suit the shape of the back to be clamped. The brush-backs to be drilled are designated 20, and those which are drilled and ready for the placing of bristle-tufts therein are designated 20^a. 45 The brush-backs of each set may be of the same or of different styles and shapes, as it may be desired to make the same style or different style brushes at the same time.

50 The plates 9 and 10 are normally caused to move together as a single unit by the provision of a spring-finger or detent 21 on one of such plates, the plate 10 in the present instance, and a coacting recessed or notched part 22 on the other plate, as best shown in Fig. 6. The part 22 is provided with two

notches from one to the other of which the detent 21 may move under pressure whereby to yieldingly hold the plates 9 and 10 in either one of two positions of relative adjustment.

The means employed, in the present instance, for imparting relative movements to the plates 9 and 10 is as follows: Pivoted, as at 23, to the top edge of the slide-plate 9 is a rocker-dog 24, which has one end portion apertured to loosely receive a pin 25 projecting upward from the top edge of the holder-plate 10 and has its other end formed with a V-notch, as shown, for engaging with a fixed pin 26 on the top edge of the carrier-head 8 when the plates 9 and 10 are moved in one or the other direction relative thereto, as the case may be. When the plates 9 and 10 are in one or the other of their relative positions of adjustment, the dog 24 is inclined or stands at an oblique angle to the top edges of the slide-parts 8, 9 and 10 with the point of the V-notched end thereof which is adjacent to the pin 26 in position to pass freely under said pin and with the other point of such end of the dog disposed in the path of movement of said pin, as shown in Fig. 6. Upon a movement of the plates 9 and 10 to the right from the position shown in Fig. 6, the right-hand point of the notched end of the dog will pass under the pin 26 and the left-hand point of such end will move in contact with the pin so that a continued movement of the plates 9 and 10 relative to the plate 8 will impart a rocking movement to the dog 24 and a consequent relative movement to the plates 9 and 10 sufficient to move the detent 21 into engagement with the right-hand notch of the coacting part 22. When the plates 9 and 10 are in either one of their relative positions of adjustment the pin 26 will stand spaced a predetermined distance from the upstanding one of the points at the notched end of the dog 24 so as to permit the plates 9 and 10 to have limited reciprocatory movements together relative to the carrying-head 8 without effecting a tripping of the dog 24 and a consequent shifting of the relative positions of said plates. The purpose of the plate-shifting dog 24 will be hereinafter more fully described.

A large ratchet-wheel 27 is mounted within the opening of the frame-part 1 on a shaft 28 therein, and fixed to the opposite sides of this wheel are the pattern cam-wheels 29 and 30, the former of which determines the vertical reciprocatory movements of the carrying-head 8, while the latter determines the horizontal reciprocatory movements of the slide-plate 9 relative to the carrying-head 8. 31 and 32 designate vertically movable slide-members which are suitably mounted for such purpose, one at each side of the wheel 27 in guideways 33 pro-

vided in the respective sides of the frame 1 within the opening thereof, as shown in Figs. 2 and 4. The slide-member 31 has a stud or roll 34 projecting therefrom and resting upon the top of the cam-wheel 29, and the upper end of this slide is provided with a head 31^a having a flat top edge upon which a roll 35, that is carried by a horizontally disposed lever 36, travels, whereby vertical movements of the slide 31 impart vertical rocking movements to said lever. The rear end of the lever 36 is fulcrumed to a bearing-standard 37 rising from the rear end portion of the slide-table 5, and its forward end has an upward bearing against the under side of a yoke or cross-piece 38, which is disposed at the rear side of the guide-plate 6 and is rigidly attached to registering portions of the carrying-head 8 by screws or in any other suitable manner, as best shown in Figs. 1, 5, 6 and 7. It is thus evident that a raising and lowering of the slide-member 31 communicates similar movements to the head 8 and parts carried thereby on the guide 6.

The slide 32 carries a stud or roll 39 in position to ride on the top edge of the pattern-wheel 30 whereby a rotation of such wheel communicates predetermined reciprocatory movements to said slide according to the formation of the wheel periphery. A bell-crank lever 40 is fulcrumed for vertical rocking movements to a bracket-arm 41 projecting from the left side of the frame 1, and this lever has one arm projecting upward and forward from its fulcrum and carrying an anti-friction roll 42 in outward thrust contact with a plate 43, which is disposed at the rear side of the left end portion of the carrier head 8 and has arms 44 extending over and under the same and fixedly attached to the adjacent end of the slide-plate 9. The other arm of the lever 40 projects inwardly through a registering opening 45 in the adjacent side of the frame-part 1 and rests loosely on a lug 46 projecting into said opening from the slide 32.

A finger 47 projects rearwardly from the right hand end of the slide-plate 9 and has a cable 48 projecting therefrom longitudinally of the slide-plate over a sheave 49 and carrying a weight 50 at its free end. The sheave 49 is carried by an arm 51 projecting rearwardly from the frame-part 2. It is thus evident that the weight 50 urges the slide-plate 9 to have movements in a direction to maintain the plate 43 in thrust contact with the roller at the end of the lever 40, and that the slide-plate 9 is moved in the opposite direction against the resistance of the weight 50 by an upward movement of the slide 32, which effects an outward rocking movement of the upright arm of the lever 40.

85 The peripheral shapes or forms of the

pattern-wheels 29 and 30 are not specifically described, as such shapes are changed to suit the size and styles of the brush-backs and the relative positioning and spacing of the holes and bristle-tufts in respective blocks, and no claim is therefore made to any specific form of pattern-wheels.

When the work-holder plate 10 is provided with two pair of brush-back clamping parts at each end portion thereof, as shown in the present instance, the pairs of the sets are so arranged that when a brush-back carried by a clamp of one set is in working register with the drill 3^a the brush-back carried by the corresponding clamp of the other set is in working register with the filler nozzle 4. During a drilling and filling of the respective brush-backs 20 and 20^a which are in register with the drilling and filler parts, the plates 9 and 10 move together as a unit with the dog 24 working at one side only of the pin 26, the movement of such plates being determined by the formation of the pattern-cam 30, whereby to properly direct the successive placing of the holes in one brush-back and the bristle-tufts in the other brush-back as the work continues. Upon the completion of the drilling and filling of the respective brush-backs 20 and 20^a which are in register with the drilling and filler parts, the pattern-wheel 30 and parts connecting it with the slide-plate, and the dog 24 and associated parts will coöperate to effect a sudden shifting of the work-holder plate 10 a sufficient distance in one direction or the other, as the case may be, to move the brush-backs 20 and 20^a carried thereby, and which have not been operated on, into working register with the respective drilling and filler parts.

It will be understood from the previous description of the dog 24 and its coacting parts that upon a sufficient predetermined movement of the plates 9 and 10 in unison to cause the dog 24 to coact with the pin 26 whereby to cause a shifting or rocking of such dog, that the work-holder plate 10 will have a greater movement than the plate 9, or in other words a sufficient movement to place the spring detent 21 into engagement with the other notch in the part 22. The augmenting of the plate moving or controlling action of the pattern-wheel 30 by the action of the dog means 24, 25, 26 prevents the necessity of providing the wheel 30 with as abrupt or decided a shifting surface as would otherwise be the case.

In order to shorten the length of the jumping movements of the brush-back holder-plate 10 during the shifting of different brush-backs into operative position, it is preferable to so direct the vertical and horizontal movements of the plate 10 that the commencement and completion of the drilling and filling operations of the brush-backs

of respective sets will be at or near the adjacent edges thereof. To illustrate, let the point *a* in Fig. 8 designate the point at which the drilling or filling operation for 5 a set of brushes starts, and *b* the point on the same brush-back at which the drilling or filling operation of such back is completed. The progress of the successive drilling or filling operation on the brush-back 10 intermediate the points *a* and *b* may take the course indicated by the arrows in the left brush-back or it may take any other desired or suitable course. When the drilling or filling of one brush-back has been 15 completed each set of brush-backs is moved so that the drilling or filling operation will commence at the point *c* on the next back to be operated on, and such operation will thence continue in any desired course on 20 such brush back and preferably terminates at or adjacent to the point *d*, which is opposite and adjacent to the starting point *a* on the companion brush-back. It will be understood that the starting and stopping 25 points on the respective brush-backs shown in Fig. 8 are merely illustrative, and that the operation of the machine is not restricted to such diagram.

52 designates the main drive-shaft of the 30 machine. This shaft is journaled in the part 2 transversely thereof and, in the present instance, carries a loose belt pulley 53 and axially shiftable coacting clutch member 54 at one end and a crank-wheel 55 at 35 its other end. A shipper-lever 56 for the clutch member 54 is fulcrumed to the frame-part 2 at one end and has its other end connected to a treadle-rod 57 through the medium of a link 58 and bell-crank lever connection 59. A spring 57a acts on the treadle-rod 57 to urge the connected clutch parts out 40 of engagement.

A catch member 60 is pivoted to the frame-part 2 and is adapted to engage a 45 projection 61 on the link 58 to retain the shipper-lever 56 in clutch engaging position. The catch member 60 has connection with a hand control lever 62 through the medium of a link 63, and such link also has connection 50 through a rod 64 with a rocker-arm 65 on a shaft 66, which shaft is journaled in the rear portion of the frame part 1 and has an arm 67 projecting therefrom into position to be engaged and moved by a pin 55 68 on the ratchet-wheel 27 at each revolution of said ratchet wheel when the catch member 60 is in engagement with the projection 61. A coiled contractile spring 69, which connects the lever 62 to a part of the 60 frame 2, acts on such lever and connected parts to urge the catch-member 60 into position to engage the projection 61 and retain the clutch parts in engagement, as shown in Fig. 3. When the pin 68 on the ratchet-wheel 27 coacts with the arm 67, such arm is

rocked a predetermined extent and a consequent clutch releasing movement imparted to the member 60.

The crank-wheel 55 has its crank-pin connected, in the present instance, by a link 70 to a vertically-disposed lever 71, which is fulcrumed at its lower end to the frame-part 2 and has its upper end connected to the filler-plunger 72, whereby a bristle-tuft ejecting movement is imparted to the plunger 72 at each revolution of said crank-wheel. The lever 71 also has connection through a rod 73 with the lower end of a vertically-disposed lever 74, which is fulcrumed to one side of the frame-part 1, as at 75 75, and has its upper end in link connection, as at 76, with the rear end portion of the slide 5. The lever 74 in addition to serving to communicate predetermined reciprocatory movements to the table 5 from the rod 73 80 also has connection at one end with a pawl 77, which is in driving connection with the ratchet-wheel teeth. The connection between the lever 74 and pawl 77, in the present instance, comprises a rock-shaft 78, 85 which is fulcrumed to the frame-part 1, a rocker-lever 79 carried thereby, and a rocker-arm 80 which is also carried by the shaft 78 and carries the pawl 77 at its outer end. A spring 81 yieldingly urges the upper end of the rocker-lever 79 in stop-contact with a stud 82 on the frame 1. A finger 83 is fixed to and projects from the lever 74 and has thrust contact with the lower end of the lever 79 in position to oppose the pull 90 of the spring 81 on the lever. It is thus evident that a movement of the lever 74 in one direction will impart a positive rocking movement to the lever 79 against the tension of the spring 81 and move the pawl 77 in 100 wheel driving direction, and that a movement of the lever 74 in the opposite direction will permit the spring 81 to retract the lever 79 and effect a back dragging of the pawl 77 relative to the ratchet wheel. The 105 specific construction of this mechanism is not pertinent to the present application and is therefore not described in detail.

An adjustable screw 84 is carried by the rear end portion of the table 5 and coacts with an alining portion of the frame 1 to limit the forward movements of the table. If there is any rearward movement of the rod 73 after the stop-screw 84 strikes the alining frame part, such movement is compensated for by a yielding connection 85 between the rod 73 and lever 74.

A bevel gear 86 is fixed, in the present instance, to the outer side of the pattern-wheel 29 and has a pinion 87 in driving mesh therewith. The pinion 87 is carried by a shaft 88, which extends on an upward incline from the gear 86, being mounted in suitable bearings 89 and carries a hand control wheel 90 at its upper end. The purpose of this hand 125 130

drive for the ratchet-wheel 27 is to enable such wheel, when the pawl 77 has been released from engagement therewith, to be turned backward or forward a predetermined distance to permit the refilling of one or more holes in a brush-back with bristle-tufts in case of an improper feeding of bristle-tufts therein in the first instance.

The operation of my improved machine is as follows: The operator having clamped a pair of brush-backs 20, either of the same or different styles, to the work-holder plate 10 at one side of its center and having clamped a pair of drilled brush-backs 20^a, either of the same or different styles, to said holder-plate at the other side of its center, depresses the treadle-bar 57 to throw the clutch-member 54 into engagement with the drive-pulley or member 53 to start the machine. As intermittent or step by step rotary movements are imparted to the ratchet-wheel 27 during a running of the machine the pattern-wheel 29 moves the slide 31 and co-acting lever 36 to impart vertical reciprocating movements to the carrier-head 8 as the drilling and filling of holes in respective brush-backs in upward and downward extending rows may require. The vertical spacing of holes in the brush-backs and the placing of bristle-tufts therein is determined either by the length of each intermittent movement of the ratchet-wheel or by the formation of the cam surface of the pattern-wheel 29, as may be convenient or desired. The rotation of the pattern-wheel 30 in unison with the pattern-wheel 29 co-operates with the mechanism connecting such wheel to the slide-plate 9 and with the weight 50 to control and direct the horizontal reciprocating movements of the plates 9 and 10 relative to the head 8 during the vertical reciprocating movements of such head, so as to determine the horizontal spacing of the vertical extending rows of holes in the brush-backs and the placing of the bristles therein and also the course or form of such vertical rows. When the drilling of a brush-back of one pair and the filling of a brush-back of the other pair have been completed the holder-plate 10 will have moved into position to place the driller and filler parts at the edges of the respective brush-backs being operated on in adjacent relation to the other brush-backs of the respective pair. At this point, the mechanism controlling the unitary horizontal movements of the plates 9 and 10 shifts such plates a sufficient extent in one direction or the other as the case may be to cause the stationary pin 26 to coact with and swing the dog 24 on its pivot, which movement of the dog effects a relative shifting of the plates 9 and 10 and a projection or movement of the holder-plate 10 into position to place the other brush-back of each pair into position to be operated on by

the respective drilling and filler parts. When the respective drilling and filling of these brush-backs has been completed and the holder-plate 10 has returned to its initial starting position, the ratchet-wheel 27 will have moved a sufficient distance for the pin 68 to strike and rock the trip-arm 67, whereby to effect an automatic stopping of the machine due to the throwing of the catch member 60 from engagement with the part 61 of the clutch mechanism.

It is evident that while I have shown my machine as adapted for the drilling and filling of successive brushes of respective pairs without stopping, the invention is not limited to any particular number of brush-backs successively operated on in this manner, but contemplates the successive filling and drilling of a plurality of brush-backs of respective sets in a continuous operation, which backs may be of the same or different styles depending upon the formation of the pattern-wheels.

It is to be understood that my invention is not limited to any specific construction or arrangement of the parts except in so far as such limitations are specified in the claims.

Having thus described my invention, what I claim as new and desire to secure by Letters Patent, is,

1. In combination, a work-holder mounted for compound rectilinear reciprocatory movements at right angles to each other and in the same plane, mechanism for imparting predetermined movements of said character to the work-holder, said work-holder comprising two body parts which are connected for relative rectilinear reciprocatory movements in the direction of one of the reciprocatory movements of the work-holder, and means operable at a predetermined point in the movements of said work-holder to impart relative movements to the parts thereof.

2. In combination, a work-holder mounted for compound rectilinear reciprocatory movements at right angles to each other and in the same plane and comprising a body part and a work-carrying part which are connected for relative rectilinear reciprocatory movements in the direction of one of the reciprocatory movements of the work-holder, means yieldingly retaining the work-holder parts at one position or another of their relative movements, mechanism operable to control the compound movements of the work-holder, and means automatically operable upon a predetermined movement of the work-holder in one plane of its movement to shift the relative positions of the work-holder parts.

3. In combination, a work-holder mounted for compound reciprocatory movements in different lines in the same plane and comprising a back plate and a face plate which

- are connected for relative reciprocatory movements in the direction of movement of the work-holder, means yieldingly retaining said plates in one position or another of their relative movements, a plurality of sets of work-holding clamps carried by said face plate, mechanism for imparting predetermined compound movements to said work-holder, and means automatically operable at 5 predetermined points in the movement of said work-holder to relatively shift the plates of the work-holder to move one clamp set from and another clamp set to operative position.
- 15 4. In combination, a movable work-holder comprising two plates connected for relative rectilinear movements, one plate having a plurality of work-carrying means, mechanism for imparting predetermined movements to the work-holder as a unit, and means operable at a predetermined point in the unitary movement of the work-holder to relatively move the plates thereof to shift one work holding means from and another 20 work holding means of the work-holder into operative position.
5. In combination, a vertical guide member, a carrier head mounted on said member for vertical reciprocatory movements, a 25 work-holder carried by said head for horizontal reciprocatory movements and comprising two body plates connected for relative shifting movements in the plane of movements of the work-holder relative to the carrier head, mechanism operable to impart predetermined movements to said carrier head and work-holder relative to each other and to said guide member, and means automatically operable at a predetermined 30 point in a movement of the work-holder relative to the carrying head to impart predetermined relative shifting movements to the body plates of the work-holder.
6. In combination, a carrier head, a work 35 holder carried for horizontal rectilinear movements by said head, mechanism for imparting predetermined backward and forward movements to said holder relative to the head, and means operable at predetermined intervals to quickly move said work 40 holder in the line of its reciprocatory movements to augment the holder moving action of said mechanism.
7. In combination, a work-holder having 45 relatively movable parts, mechanism operable to impart predetermined movements in unison to said work-holder parts, and means operable at predetermined intervals to impart relative movements to said holder parts in the direction of movement of the holder to augment the holder moving action of said mechanism.
8. In combination, a work-holder having 50 relatively movable parts, means permitting said parts to have limited reciprocatory 55 movements in unison and operable to impart relative movements thereto upon a predetermined unitary movement thereof, and mechanism operable to impart predetermined reciprocatory movements in unison to said 60 holder parts.
9. In combination, a holder having relatively movable parts, means for yieldingly holding said parts in predetermined positions of relative adjustment, mechanism 65 operable to impart predetermined reciprocatory movements in unison to said holder parts, and means operable at predetermined points in the unitary movements of said parts to impart predetermined relative 70 movements to the parts.
10. In combination, a guide-member, a work-holder guided for reciprocatory movements by said member and having relatively movable parts, means resisting a relative 75 movement of the holder parts, a dog pivoted to one of said parts and having engagement at one side of its pivot with the other part and at the other side of its pivot with said guide member whereby a predetermined 80 movement of one holder part relatively to the guide member will impart movement to the other holder part relative to the guide member, and mechanism for imparting predetermined reciprocatory movements to said 85 holder parts.
11. In combination, a guide-member, a work-holder carried for reciprocatory movements by said member and having parts which are relatively movable in the direction of movement of the holder, means resisting the relative movements of the holder parts, a rocker element pivoted to one of said parts and having one end in pivotal connection with the other of said parts and its other end notched to coat with an alining fixed portion of the guide-member to 90 impart relative reciprocatory movements to said holder parts at a predetermined point in a movement of the holder in either direction relative to the guide-member; and means for imparting predetermined reciprocatory movements to said work-holder.
12. In combination, a reciprocatory carrier-head, a work-holder carried for reciprocatory movements by said head and having relatively movable parts, mechanism imparting predetermined reciprocatory movements to said carrier-head and work-holder respectively, and means for imparting predetermined relative movements to the holder parts at predetermined points in the movements of the work-holder relative to the carrier-head.
13. In combination, a reciprocatory carrier-head, a work-holder carried by said head for reciprocatory movements at an angle to the movement of the head in the plane of movement thereof, and having relatively movable parts, means resisting a rela- 100 105 110 115 120 125 130

tive movement of said parts, mechanism for imparting respective reciprocatory movements to said head and work-holder, and means operable at predetermined intervals 5 in an operation of said mechanism to impart relative shifting movements to said holder parts.

14. In combination, a work holder, mechanism for imparting predetermined rectilinear movements at right angles to each other to said work holder, and means operable at predetermined intervals in an operation of said mechanism to augment one of the rectilinear work holder moving actions 10 of said mechanism.

15. In combination, a carrier head, a work-holder carried for reciprocatory movements by said head and comprising relatively reciprocatory back and face members; 20 means resisting a relative movement of said members, mechanism for imparting predetermined reciprocatory movements to the work-holder, and means having a lever operable to impart relatively reciprocatory movements to the members of the work-holder at a predetermined point in a movement 25 of the work-holder.

16. In combination, a reciprocatory carrier-head, means for imparting movements thereto, a work-holder carried for reciprocatory movements by said head and having relatively movable parts, means resisting a relative movement of said parts, mechanism for imparting reciprocatory movements to 30 said work-holder at an angle to the movement of said head in the plane therewith, and means for relatively shifting the holder parts at a predetermined point in the movements of the work-holder relative to said 35 head.

17. In combination, a reciprocably movable work-holder having provision for carrying a plurality of work-pieces to be drilled and a plurality of work-pieces to be filled, 45 drilling means and filling means operable to simultaneously act on a single work-piece of the respective sets, and mechanism operable to impart predetermined movements to said holder during a drilling of a work-piece of one set and a filling of a work-piece of another set carried thereby, then to move the holder into position to place another work-piece of each set into register with the respective drilling and filling 55 means.

18. In combination, a drilling means, and a filler means, a reciprocably movable work-holder having provision for the carrying of separate sets of work-pieces to be drilled 60 and work-pieces to be filled, and mechanism operable to move the work-holder to successively and simultaneously place different work-pieces of the respective sets into register with the associated drilling and filler 65 means and to move the work-holder to suit

the drilling and filling of each work piece of the respective sets.

19. In combination, drilling means and filling means, a work-holder having provision for the carrying of separate sets of 70 work pieces for respective drilling and filling operations, mechanism for imparting predetermined movements to the work-holder during a simultaneous action of the drilling and filler means on registering 75 work-pieces of respective sets, and means operable at predetermined intervals to co-operate with said mechanism to move said work-holder to successively place different work-pieces of the sets in respective register 80 with the drilling and filler means.

20. In combination, a rectilinearly movable table, means carried by said table for reciprocatory movements in a plane at variance to the movements thereof, a work-holder reciprocably carried by said means, and mechanism operable to impart predetermined movements to said table, means 85 and holder respectively.

21. In combination, a horizontally movable table, means carried by said table for reciprocatory movements relative thereto, a work-holder carried by said means for reciprocatory movements in a plane at variance to the planes of reciprocatory movements of said table and in the plane of movement of said means, and mechanism operable to impart predetermined reciprocatory movements to said table, means and work-holder respectively. 90

22. In combination, a rectilinearly reciprocatory member, a carrier-head guided by said member for reciprocatory movements in a plane at variance to the plane of reciprocatory movements of the member, a work-holder carried by said head for rectilinear reciprocatory movements at an angle to the movements of said head in the plane therewith and having relatively movable parts, mechanism for imparting predetermined movements to said member, carrier-head and work-holder respectively, and means for imparting predetermined relative movements to the parts of the holder at predetermined points in a movement of 105 the holder relative to the carrying-head. 110

23. In combination, a reciprocatory table, work-carrying means movably carried by said table, a lever fulcrumed to a part of the table and having engagement with said means, and mechanism operating on said lever to control the movements of the same and the consequent movements of said means. 120

24. In combination, a reciprocatory table, 125 a bearing standard rising therefrom, work-carrying means carried for reciprocatory movements by said table in a plane at variance to the plane of movement of the table, a rotatable pattern wheel below the table, a 130

- slide having its movements directed by said pattern wheel and movable in the plane of movement of said means, a lever fulcrumed to said standard with an end in 5 supporting engagement with said means and having a part resting freely on said slide whereby movements are communicated from the slide to said means through the lever.
- 10 25. In combination, a rectilinearly reciprocating carrier-head, a work-holder carried by said head for rectilinear reciprocating movements at an angle to the movements of said head in the plane therewith, 15 means operable to direct the movements of said head, a pattern-wheel, a lever having connection with and having its rocking movements controlled by said wheel and acting against a part of said work-holder to 20 move the same in one direction, and means

urging a movement of the work-holder in the opposite direction.

26. In combination, a horizontally reciprocating table having a vertical guide part, a work-holder guided for vertical movements by said part, a pattern wheel, a vertically movable slide actuated by movements of said pattern wheel, and a lever fulcrumed to said table and having a part in engagement with the work-holder whereby movements are communicated from the slide through the lever to the work-holder. 25

30 In testimony whereof, I have hereunto signed my name to this specification in the presence of two subscribing witnesses.

CONRAD JOBST.
